UNITED STATES PATENT OFFICE.

AMBROSE EVERTS GREENE, OF CORNING, CALIFORNIA.

ROTARY ENGINE.

Application filed April 17, 1919. Serial No. 290,811.

To all whom it may concern:

Be it known that I, AMBROSE E. GREENE, a citizen of the United States, residing at Corning, in the county of Tehama and State 5 of California, have invented certain new and useful Improvements in Rotary Engines, of which the following is a specification.

My invention relates to rotary engines, 10 and the like, and has for one of its objects the provision of a simple and efficient engine, or the like.

A further object is the provision of a engine, or the like, as mentioned, in which 15 friction and vibrations are reduced to a minimum.

A further object is the provision of a rotary engine, or the like, in which the charges are compressed in the engine cylinders in 20 which they are to be fired.

A further object is the provision of a rotary engine, or the like, in which a rotative balance is had at all speeds.

A still further object is the provision of 25 an engine, or the like, such as mentioned, in which the movement of the pistons in their cylinders causes rotary movements of the pistons and cylinders about a common axis.

Other objects will appear hereinafter.

An embodiment of my invention is illustrated in the accompanying drawings, forming 30 a part of this specification, and in which—

Fig. 1 is a plan view of a rotary engine 35 embodying my invention;

Fig. 2 is a side elevation of the same;

Figs. 3 and 4 are sections taken on lines 3—3 and 4—4, respectively, of Fig. 1;

Fig. 5 is a section taken substantially on 40 line 5—5 of Fig. 4; and

Fig. 6 is a detail illustrating a modified form of cam used in the construction.

In the drawings I have illustrated an 45 internal combustion engine to show the application of my invention. By a slight modification, as hereinafter described, the construction may be used as a steam or other fluid under pressure engine.

Referring more particularly to the drawings, I have shown a substantially rectangu-

lar frame 8, see Fig. 1, mounted on supporting legs 9. It will be apparent, however, that the form of the frame and its supports may be varied, as desired. On the two longitudinal sides of the frame 8 I provide 55 bearing blocks 10 in which is journaled a shaft 11. When so desired, ball-bearings 12 may be provided between the bearing blocks 10 and the shaft 11, see Fig. 5. The bearing blocks 10 may be secured to the frame 8 in 60 any desirable manner, such as by bolts 13, or the bearing blocks and the frame may be formed in any other desirable manner.

I provide cylinders and pistons to operate in the cylinders, with the pistons and cylinders adapted to rotate about the axis of shaft 11. I preferably mount the cylinders in such a manner that they rotate with the shaft, and the pistons have an oscillatory movement with respect to the cylinders, but 70 this arrangement may be varied by causing the pistons to move with the shaft, and the cylinders to oscillate with respect to the pistons. Secured to the shaft I have illustrated a central hollow block member 14 which may 75 be secured to the shaft 11 in any desirable manner, such as by a key 15, see Fig. 5. The hollow block member 14 is preferably provided with a plate 16 which closes the open side thereof. The plate 16 also is preferably 80 secured to the shaft, as by a key 15. The hollow part 14 is provided with cylinder heads 17 which extend radially therefrom and provide supporting means for a plurality of cylinders. In the form of the invention 85 shown, I have illustrated four cylinders 19, 20, 21 and 22 which may be secured to the heads 17 in any desirable manner, such as by screws 23.

Extending through the hollow member 14 90 is a lever 24 which is journaled on the shaft 11 and extends through openings 25 in the periphery of the member 14 between the free ends of the cylinders. At each end of the lever 24 is an arcuate head 26. At one end 95 of the lever 24 is a radial extension 27, and at the other end of the lever 24 is a counter-weight 28.

The heads 26 carry pistons 29, 30, 31 and 32 which are adapted to oscillate in the cyl- 100

inders 19, 20, 21 and 22, respectively. With this arrangement the cylinders are secured to the shaft to rotate therewith, and the pistons mounted to oscillate in the cylinders on the shaft 11. Each of the pistons is provided with packing rings 33. The front and rear edges of said packing rings lie in substantially radial planes from the axis of the shaft 11. This arrangement provides a piston 10 ring which is narrower at its side next to the shaft 11, and wider at its side away from said shaft. These rings fit in grooves in the pistons of similar shapes so that the rings are held against crawling around the pistons. It will be apparent from this construction that, since the pistons are mounted on members 24 and 26 in a manner to travel in a circle about the axis of shaft 11, and the cylinders having their central lines 20 in a circle about the axis of said shaft, there will be practically no lashing of the pistons against the sides of the cylinders in their operation. Practically the only friction between the cylinders and pistons will be the 25 friction of the rings 33 on the walls of the cylinders.

The pistons may be lubricated in the cylinders in any desirable manner. As an effective and simple means I preferably provide an opening 34 in the shaft 11, see Fig. 30 5, which communicates with radial openings 35, Fig. 4, which extend from the opening 34 out through the shaft 11 and lever 24 to the heads 26 and connects with openings 36 in said heads. The openings or 35 channels 36 extend into the pistons, and thence radially of the pistons through openings 37. As many openings 37 may be provided in the pistons as desired. With such 40 a construction the oil is fed into the end of shaft 11 where it finds its way through the passage 34 to passages 35 and by centrifugal force thrown out to the passages 36 where it finds its way through the latter passages 45 through the openings 37 where the oil comes in contact with the cylinder walls to lubricate the pistons in the cylinders.

To the hollow member 14 I preferably 50 secure a lever 38, securing it by suitable means, such as rivets 39. It will be apparent, however, that the lever 38 may be attached to the member 14 in any other desirable manner. One end of the lever 38 is provided with a counterweight 40.

55 Eccentrically to the shaft 11 I provide a lever or walking beam 41. This walking beam is preferably provided with a large opening at its center so that it may pass freely around the shaft 11 in its eccentric 60 relation to the latter. The lever 41 is journaled on the bearing block 10 and may be provided with ball-bearings 42, or their equivalent, when so desired. I preferably 65 use two of the walking beams or levers 41, substantially as indicated in Fig. 5; and con-

nect the ends thereof together by shafts 43. The shafts 43, 43' are then connected by means of links 44, 44' with shafts 46 and 45. The shaft 45 is mounted in one end of lever 38, and the shaft 46 is mounted in 70 one end of lever 27. Each of the links 44, 44' is preferably provided with a counterweight 48, the counterweights 48 being arranged so that they counterbalance the links 44, 44' and the counterweights 28 and 75 40 being arranged with relation to the counterweights 48 so that the whole structure is substantially accurately balanced.

A fuel intake pipe 49 is fitted in an opening 50 in one of the bearing blocks 10, see 80 Fig. 5. A plate 51 is secured to said bearing block 10 and provided with an opening 52 therein registering with the opening 50. A passage 53 leads from the hub portion of block 14 substantially radially out into each of the heads 17 and terminates in chambers 54 and 55. Opening from the chamber 54 are two valves 56 and 57 which control the passage of fuel from the chamber 54 into the compression space 58 of cylinder 19, and compression space 59 of cylinder 20. The chamber 55 opens through valves 60 and 61 into compression space 62 of cylinder 21, and compression space 63 of cylinder 22. Each of the valves 56, 57, 60 and 61 is operated by a tappet 64 which is mounted on a pin 65 carried in the block 14. Each tappet 64 carries a roller 66 at one end which cooperates with a cam shaft 67. The cam shafts 67 are mounted in the members 14 and 16 and actuated by gears 68 on the outside of member 16. Each cam shaft 67 has a cam 69 adapted to control said valves 56, 57, 60 and 61. Each of the compression spaces 58, 59, 62 and 63 opens 90 through an exhaust valve 70, two of which are shown in Fig. 5, the other exhaust valves being hidden or cut away in all of the views. Each of the exhaust valves communicates with exhaust chambers 71, see 100 Fig. 5. I have shown the exhaust chambers 71 as opening directly into the atmosphere, but it will be understood that when it is desired, passages corresponding to passages 53, 52 and 50 may be provided 110 to conduct the exhaust gases out through the block 10 opposite to the one which conducts the fuel into the engine. Each of the valves 70 is operated by a tappet 72 (similar to the tappets 64) which cooperates 120 with a cam 73 on one of the cam shafts 67. The gears 68 mesh with a pinion 74 which is preferably secured to one of the bearing blocks 10 and adapted to permit shaft 11 to rotate in it. Since the pinion 74 is 125 held stationary and the gears revolve about it, rotation will be given to said gears 68, causing rotation of the cam shafts.

A spark plug has its spark-producing end 130 reaching into each of the compression cham-

bers 58, 59, 62 and 63. The spark plugs are connected to brushes 76 by suitable wiring 77, see Fig. 2. In the present invention I preferably connect the spark plugs which communicate with chambers 58 and 62 with one brush 76, and the other two spark plugs with the other brush 76 so that explosions occur simultaneously in cylinders 19 and 21, and explosions occur simultaneously in cylinders 20 and 22. The brushes 76 engage with contactors 78 and 78', and the latter are connected by means of suitable wires 82 and 82' with points 80 and 79, respectively, of a distributor. A suitable source of power, such as an electric battery 81, is connected to the connection 81' of the distributor, the other side of the battery 81 being connected to the frame to complete the circuit. A pinion 83 is mounted on the shaft 11 and meshes with a gear 84 on the distributor to cause operation of the latter.

The cams on the cam shafts 67 and other parts of the engine are so arranged that charges will be introduced into the cylinders 19 and 20 simultaneously, and in the cylinders 20 and 22 simultaneously. This arrangement provides a construction in which explosions take place at diametrically opposite sides of the shaft at the same time, thereby reducing strains and vibrations in the engine to a minimum.

The taking of fuel into the cylinders, compressing such fuel, firing the charge, and exhausting the burnt gases are all accomplished in this engine in substantially the same manner as in the ordinary four-stroke cycle internal combustion engine. The pistons oscillate in their respective cylinders because the cylinders are connected to one end of the lever 41, and the pistons are connected to the other end of such lever 41, and the latter mounted eccentrically to the axis of the pistons and cylinders. This arrangement causes each piston to move from one end of the cylinder to the other, and back to the place of beginning during each complete revolution of the shaft 11 and lever 41.

A charge is fired in each of the cylinders in substantially the same manner; therefore, in following the operation in one cylinder, the operation of all of them will be apparent. In the movement of lever 41 through a half circle, cam 69 will raise valve 57 to permit the movement of piston 29 to draw in a charge of fuel, and bring the piston 29 to the opposite end of cylinder 19. In this movement of lever 41, levers 24 and 38 will be rotated until each takes the place of the other lever. Then upon rotating the lever 41 through another half circle to the position shown in Fig. 4, the piston 29 will be brought to its position shown in Fig. 4, compressing the fuel ready for firing. Le-

vers 24 and 38 will also be brought to their positions indicated in this figure. Then upon rotation of the lever 41 through another half circle, the charge will be fired, and upon completion of this revolution of the lever 41, exhaust valve 70 will be opened scavenging said cylinder and bringing the parts to the position shown in Fig. 4 ready for a new cycle. During the working stroke pressure was applied to the adjacent sides of piston 29 and cylinder head 17 in substantially equal pressures. These pressures were transmitted through levers 38 and 24 to opposite ends of lever 41 causing equal forces to be applied to said lever 41. Due to the lever 41 being mounted eccentrically to shaft 11 and the particular part of the revolution of the parts through which the latter were passing when the explosion occurred, greater leverage is applied to the end of lever 41 which is connected with the cylinder head 17, therefore, the engine is caused to rotate in a clockwise direction. The parts are so timed that the charges are fired in cylinders 20 and 22 when the engine is in a part of its revolution where greater leverage is produced on the end of lever 41 connected with pistons 30 and 32, thereby causing another impulse also in a clockwise direction in the engine. It will therefore be seen that due to the particular arrangement of the parts the explosions in cylinders 19 and 21 cause an impulse in a clockwise direction, and the explosions in cylinders 20 and 22 cause another impulse in a clockwise direction.

It is found that by slight alteration the device is adapted to use compressed air or steam as a motive power. The only changes necessary is to make gears 68 and 74 of equal sizes so that cam shafts 67 rotate in a relation to shaft 11 of "one to one." Also, to change the cams 69 and 73, substantially as indicated in Fig. 6, so that the intake valves will be open throughout the greater portion of the first half of the revolution of the engine, and the exhaust valves open through most of the remaining half of a revolution of the engine. It will thus be seen that in using steam or other compressed fluid that the engine operates in a two-stroke cycle. When the device is arranged as just mentioned, power may be applied to shaft 11 and the device used as a pump or compressor.

It should be noted that the cylinders 19, 20, 21 and 22 are rigidly connected together and are rigidly connected to the frame 14, 16 shown in Fig. 5 and this frame is keyed at 15, 15 to the shaft 11 to which power is transmitted by the rotation of the structure comprising the four cylinders. It should also be noted that the four pistons are rigidly connected together by being rigidly connected to the frame 24 which is connected 130

to the sleeve mounted loosely on the shaft 11, as shown in Fig. 5. The frame 24 together with the pistons are mounted on the shaft 11 concentrically with the framework which includes the cylinders. Although the supplemental frame 24 is located between the ends of the cylindrical main frame there are arcuate spaces provided for arcuate movement of the pistons along the cylinders and arcuate movement of the frame 24 relatively to the cylindrical frame. The angular spaces in the main frame are clearly shown in Fig. 4 at the right and left hand portions thereof. The walking beam frame comprising a pair of spaced-apart walking beams are mounted at both sides of the main frame, as shown in Fig. 5. Spaced-apart eccentric cams are mounted on opposite sides of the cylinder framework. It will be seen by referring to Fig. 5, that these eccentric cams are rigidly connected to the stationary frame 8 and in end view each is circular, as shown in dotted lines in Fig. 4, with the center of the circle above the axis of the shaft 11. Therefore, as the walking beams rotate around the stationary eccentric cams, the spaced-apart straps of the walking beams engage through ball bearings diametrically opposite points of the circular eccentrically mounted stationary actuating devices 10, 10. The rotary frame 24 which is mounted loosely on the shaft 11 is connected by the links 44 to the pair of walking beams 41 which are mounted to rotate freely about the journal bearings 10, 10 on an axis spaced above the axis of the shaft 11.

With the foregoing explanation as to the relation of the parts of my improved rotary internal combustion engine, the operation can be readily understood. Assuming that it is desired to operate the shaft 11 in a clockwise direction, as viewed in Fig. 4, while the cylinders are moving clockwise the explosive mixture is being introduced into the cylinders 19 and 21 and mixtures in the cylinders 20 and 22 are being compressed. Then while the mixture in the cylinders 19 and 21 are being put under compression, the mixtures in the cylinders 20 and 22 are being fired. During the next step the mixtures in the cylinders 19 and 21 are being fired while the products of combustion in cylinders 20 and 22 are being exhausted. In completing the cycles, the products of combustion in the cylinders 19 and 21 are being exhausted while the cylinders 20 and 22 are taking in new mixtures. The cycles of operations are repeated continuously in this manner.

Assuming that the pistons 29 and 31 in the cylinders 19 and 21, respectively, have been moved to positions where the mixtures in the cylinders 19 and 21 are under compression in readiness for firing, it will be seen that when the firing occurs, there will

be considerable pressure exerted on the bottoms of the cylinders 19 and 21 against the resistance offered by the pistons 29 and 31, to rotate the shaft 11 in a clockwise direction. The pistons 29 and 31 are connected to the frame 24 which is loosely mounted on the shaft 11 and it is therefore necessary to consider how the resistance against movement of the pistons is secured. When the explosions in the cylinders 19 and 21 occur, the tendency is for the frame 24 to be moved anti-clockwise.

By referring to Fig. 4 it will be seen that the link 44' occupies a position nearly perpendicular to a line extending through the axis of the shaft 43', the center about which the walking beam 41 rotates and the axis of the shaft 43. The link 44, however, is more inclined towards this radial line. It can thus be seen that the force exerted by the cylinders through the link 44' will be greater than the force exerted by the pistons acting through the link 44' on the other end of the walking beam 41. The force exerted along the link 44 might be resolved into two component forces, one acting radially from the center on which the walking beam 41 rotates, and the other acting at right angles to the radial line extending through the axes 43, 43' and the center of the cam disc. As the cylinders rotate clockwise the pivotal axis 43' will gradually approach closer to the axis of the shaft 11 while the pivotal axis 43 will gradually occupy a position farther away from the axis of the shaft 11, but as this occurs the link 44 must become more and more inclined toward the radial line through the pivotal axis 43, 43' and the center of the disc, because the pivotal axis 46 always remains at the same distance from the axis of the shaft 11 while the pivotal axis 43 becomes more distant from the axis of the shaft 11. This can readily be seen by referring to the dotted circle in Fig. 4 which shows that the center thereof is spaced above the axis of the shaft 11. At the same time that the pivotal axis 43 moves farther away from the axis of the shaft 11, the axis 43' is moving closer to the shaft 11 while the axis 45 remains constantly at the same distance on account of the lever 38 being riveted to the frame carrying the arcuate cylinders. The swing of the link 44' is toward a vertical position relative to the radial line through the axes 43 and 43' and beyond, but the inclination relative to the said radial line is not as great as that of the link 44. The resultant of the various forces acting effects a preponderance toward rotating the cylinder structure clockwise. This operation may also be explained by the fact that since the axis of the walking beam is spaced above the axis of the driving shaft, of the engine, the effective leverage gradually becomes shorter as the cylinders rotate clock-

wise from the position shown in Fig. 4. The effective leverage tending to turn the walking beam 41 anti-clockwise, is the distance from the center of the cam disc to the 5 intersection of the radial line through the center of such disc and the axis 43, and a line drawn from the axis 46 perpendicular to such radial line. Since the axis 43 moves outwardly relatively to the axis 46, 10 this leverage gradually becomes shorter. At the start, where the parts are related, as shown in Fig. 4, this leverage is less on the left hand side than on the right hand side. On the right hand side the link 44' swings 15 toward the right. This will effect an increase of the leverage as determined by a line drawn from the axis 45 perpendicular to the radial line through the center of the disc and the axis 43'. That is to say, the distance 20 between the intersection of such perpendicular line and the radial line from the axis of movement of the walking beam gradually increases as the cylinders rotate. The various parts of the multiple rotary internal 25 combustion engine are so related to each other, that whenever explosions in the cylinders take place, the resultant of the forces will act to continue to rotate the cylindrical structure and the shaft 11 in a clockwise direction.

Obviously those skilled in the art may make various changes in details and arrangements of parts without departing from the spirit and scope of my invention as defined 35 by the claims here appended, and I wish, therefore, not to be restricted to the exact construction herein disclosed.

I claim:

1. In combination, a shaft; a member 40 fixed on said shaft; cylinder heads on opposite sides of said member; an engine cylinder attached to each cylinder head; a lever pivoted on said shaft; pistons carried on said lever and disposed in said cylinders; a lever mounted eccentrically to said shaft; connecting links connecting the last-mentioned lever with the first-mentioned lever and said member adapted to effect relative oscillatory movements between the cylinder heads 45 and pistons; and counterweights on said links, member and first-mentioned lever.
2. In combination, a shaft; a member 50 fixed on said shaft; cylinders attached to said member; a lever pivoted on said shaft; pistons attached to said lever and disposed in said cylinders; a lever pivoted eccentrically to said shaft; connecting links connecting said lever together; and counterweights on said links.
3. In a rotary engine, the combination 55 with a rotary shaft, of a cylinder and its cylinder head located concentrically of said shaft, a piston mounted upon said shaft, a pair of interconnected stationary discs with their centers located eccentrically of the 60 axis of said shaft, and means comprising oscillating links connected between said discs and said piston and between said discs and said shaft to effect the rotation of the latter for an operation of the source of power within said cylinder against the piston and the cylinder head.
4. In a rotary engine, the combination 65 with a plurality of concentrically mounted rotary elements, of mechanism for alternately accelerating and retarding the respective angular velocities of the rotary elements during each complete rotation, said mechanism comprising a pair of stationary discs in spaced-apart vertical planes at opposite sides of said elements having an axis of rotation eccentric of the axis of rotation of said rotary elements, a pair of spaced-apart walking beams mounted respectively on said discs to have an axis of rotation 70 eccentric of the axis of rotation of said rotary elements, means for connecting the outer ends of the walking beams, and oscillating links between said connecting means and said rotary elements.
5. In a rotary engine, the combination 75 with a stationary supporting frame, of a rotary shaft mounted thereon, spaced-apart discs secured to said supporting frame with their centers in alinement and spaced from 80 said shaft, a rotary frame mounted on said shaft, a plurality of tubular members in arcuate alinement and comprising arcuate tubular expansion chambers mounted on said rotary frame concentrically of said 85 shaft, a plurality of pistons, one in each of said tubular members, a piston frame mounted loosely on said shaft for movement of said pistons arcuately concentrically of said 90 shaft, spaced-apart rotary frames mounted 95 on said discs, means for connecting said spaced-apart rotary frames to rotate together on the center of said discs eccentrically of the axis of said shaft, link structure connecting said piston frame to one end 100 of each of said spaced-apart frames on said discs, and additional link structure between said rotary frames and the other ends of said spaced-apart frames on said discs.
6. In a rotary internal combustion engine, the combination with a supporting frame, of a shaft mounted thereon, a rotary frame connected to said shaft to rotate therewith, a plurality of tubular members on said 105 rotary frame each having an arcuate combustion chamber concentric of said shaft, a plurality of pistons one movable arcuately in each of said tubular members, a piston frame mounted loosely on said shaft 110 and rigidly connecting together said pistons for movement concentrically of said shaft along said combustion chambers, circular cam structure mounted on said supporting frame eccentrically of said shaft, framework rotatable about said cam struc- 115
- 120
- 125
- 130

- ture, and link structure connecting diametrically opposite portions of said framework respectively to said rotary frame and to said piston frame to effect rotation of said shaft 5 upon the operation of the source of power in said tubular members acting on the heads of the latter and on said pistons at predetermined intervals.
7. In a rotary internal combustion engine, the combination with a supporting frame, of a shaft mounted thereon, a rotary frame mounted on said shaft to rotate therewith relatively to said supporting frame, four tubular members mounted on said rotary frame with tubular arcuate combustion chambers arranged concentrically of said shaft and in circular alinement, four pistons one for each of said combustion chambers, a piston frame mounted loosely on said shaft and rigidly connecting said pistons between the tubular members at diametrically opposite portions of said rotary frame, cam structure secured to said supporting frame eccentrically of said shaft, framework mounted on said cam structure for rotation about the same, link mechanism pivotally connected between said piston frame and one side of said framework, and additional link mechanism connected between said rotary frame and the diametrically opposite side of said framework relative to said cam structure.
8. In a rotary engine, the combination with a supporting frame, of a shaft mounted thereon, a rotary frame mounted on said shaft to rotate therewith, an arcuate tubular member mounted on said rotary frame with an arcuate expansion chamber concentric of said shaft, a piston mounted to move arcuately back and forth relatively to said tubular member, cam mechanism on said supporting frame, and means connected between said piston and said rotary frame by way of said cam mechanism to control the movements of the piston in said tubular member.
9. In combination, a frame; a disc mounted on the frame; a shaft journaled in the disc eccentrically to the center thereof; a cylinder mounted on the shaft; a piston mounted in the shaft and adapted to oscillate in the cylinder; a lever pivoted on the periphery of the disc; a connection between one end of said lever and the piston; and a connection between the other end of said lever and the cylinder.
10. In combination, a frame; a disc mounted on the frame; a shaft journaled in the disc eccentrically to the center thereof; a cylinder mounted on the shaft; a piston mounted in the shaft and adapted to oscillate in the cylinder; a lever pivoted on the periphery of the disc; a connection between one end of said lever and the piston; a connection between the other end of said lever and the cylinder; and a fuel supply pipe attached to the disc adjacent the shaft, there being a fuel passage extending from said pipe to the interior of the cylinder.
11. An engine comprising a shaft; a frame fixed on said shaft; cylinders carried by said frame and having their center lines concentric with said shaft; a counterweight on said frame; a lever mounted on said shaft; pistons attached to said lever and disposed within said cylinder; a counterweight on the lever; and an operative connection between the frame of said cylinders and the lever of said pistons controlling relative movements of the pistons and cylinders.
12. In combination, spaced discs; a shaft journaled eccentrically in said discs; levers pivoted on the peripheries of said discs; a member fixed on said shaft; cylinders attached to said member; a lever pivoted on said shafts; pistons attached to the last-mentioned lever and disposed in said cylinders; and links connecting the levers together.
13. In combination, a frame; spaced-apart discs mounted on the frame; a shaft journaled eccentrically to said discs; a rotary engine mounted on said shaft between said discs; a fuel supply pipe connected with one of said discs and communicating with the interior of the rotary engine; and means attached to one of said discs and connected with the engine for controlling the operation of the latter.
14. In combination, a frame; a shaft journaled in the frame; a cylinder fixed on said shaft and having its center line concentric with the axis of said shaft; a lever journaled on said shaft; a piston on said lever disposed within said cylinder; counterweights associated with said lever and said cylinder, said counterweights being on opposite sides of said shaft; a lever mounted eccentrically to said shaft; a connecting link connecting one end of the last-mentioned lever with the lever journaled on said shaft; a counterweight on said connecting link; a connecting link connecting the other end of said lever mounted eccentrically to said shaft and said cylinder; and a counterweight on the last-mentioned connecting link.
15. The combination with a stationary frame, of spaced-apart discs secured thereto, a shaft eccentric of said discs, a rotary engine mounted on said shaft between said discs, and means mounted on said discs and connected to said engine for controlling the operation of the latter.
16. The combination with a stationary frame, of a plurality of discs secured thereto, a shaft eccentric of said discs, a rotary engine mounted on said shaft, and means on said discs and connected to said engine for controlling the transmission of power in the latter during the operation thereof.

17. The combination with a stationary supporting frame, of spaced-apart discs secured thereto, a shaft eccentric of said discs, a rotary engine on said shaft, a pair of frames one on each of said discs and extending in opposite directions therefrom, and connections between the ends of said last-named frames and said rotary engine for controlling the transmission of power in said engine.
- 10 In testimony whereof I have signed my name to this specification on this eleventh day of April A. D. 1919.

AMBROSE EVERTS GREENE.
